PAD RECEPTACLE

Dora Madsen, San Francisco, Calif.

Application April 3, 1937, Serial No. 134,808

4 Claims. (Cl. 206—1)

My present invention relates to a scouring pad receptacle, and more particularly to a receptacle for holding a scouring pad upon a shaker type soap container.

5 An object of the invention is to provide a convenient receptacle for holding a steel wool scouring pad which can be attached to the outside of a soap container.

Another object of the invention is to provide a 10 novel form of receptacle for a single steel wool scouring pad which can be conveniently attached upon the outer wall of any cardboard container.

Another object of the invention is to provide an 15 attachable scouring pad receptacle for a soap box container having means which will retain the scouring pad against displacement when the soap container is shaken.

In the use of steel wool scouring pads of the type which consists of nothing more than steel 20 wool, as for example "Brillo", or the type having a soap ingredient combined therewith, such as "S. O. S.", the housewife often finds it desirable and necessary to use with these pads a powdered soap of the type such as is sold under the trade 25 name of "Old Dutch" cleanser and "Sunbrite" cleanser, and it is therefore a further object of this invention to provide a receptacle for retaining a scouring pad for convenient use upon such a soap container.

30 For a better understanding of my invention reference should be had to the drawing, wherein there is shown by way of illustration and not of limitation, preferred embodiments thereof.

In the drawing:

35 Figure 1 is a fragmentary perspective view showing a pad receptacle of one form secured upon the outside of a cylindrical shaker type soap container, wherein the receptacle is secured upon the soap container by means of tongues which 40 project behind the outer lithographed wrapper of the soap container.

Figure 2 is a perspective view showing a modified form of receptacle, which is particularly 45 adapted to a square type of container, such as the container in which the steel wool pads are originally sold,

50 Figure 3 is a sectional view in a vertical plane showing a further modified form of receptacle attaching means,

Figure 4 is a view similar to Figure 1, showing the scouring pad receptacle secured upon the outside of a cylindrical shaker type soap container by means of a container surrounding band, and

55 Figure 5 is a fragmentary view showing a fur-

ther modified means for attaching the receptacle to a cardboard or other container.

Steel wool pads of the character for which the receptacle of the present invention is primarily intended, are usually sold in cardboard containers 5 having from three to a dozen dry pads therein, and since the used pad entrains considerable moisture, which frequently produces rust, this pad cannot be again placed back in the original container. Therefore, in connection with the use of 10 steel wool scouring pads, such as have been referred to above, the housewife has always found it necessary to provide a receptacle, such as a saucer or cup, into which the pad may be placed after 15 use.

As stated above, these pads entrain considerable 20 water, and consequently, if they are laid on the drain board or a shelf without a suitable container, they will leave a rust spot which is difficult to remove, and since these pads often last in use 25 as long as a week, it will be readily appreciated that a receptacle into which the wet pad may be kept in a convenient manner is highly desirable.

In Figure 1 of the drawing, there is shown a 30 shaker type soap container 10 having a receptacle 11 in the form of a metal pocket 11 which fits snugly against the cylindrical part of the container 10 and holds a pad 12. The receptacle 11 is here shown as having two rearwardly and downwardly 35 extending tongues 13 which are adapted to be inserted over the top and behind the lithographed wrapper, such as is universally provided upon shaker top soap containers of the character illustrated. The pocket 11 is of such a shape that the user can, in grasping the container 10, engage the 40 pocket 11 with a finger or thumb and thus prevent its dislodgment when the soap container is shaken to discharge soap therefrom. To prevent the steel wool pad from being dislodged from the pocket in the event of such a shaking of the container 10, the outer wall of the receptacle 11 is punched 45 inwardly as at 14, so as to provide a grater-like surface on the inside thereof, which will engage the steel wool pad and prevent its falling out. At the same time this grater-like surface 14 on the 50 inside of the pocket will permit a withdrawal of the pad 12 by the user without any great effort.

In Figure 2 of the drawing, there is shown a 55 container 15, of the type in which the steel wool pads of the character contemplated, are sold, and since it is possible that the housewife may not use these pads with a shaker type soap container, as shown in Figure 1 of the drawing, my invention also contemplates a form of receptacle which may be attached to a flat sided cardboard container,

such as the one in which the scouring pads are originally sold. In this figure of the drawing, the receptacle, designated by the numeral 16, has a flat container engaging side 17 from which there 5 extends two container perforating tongues 18 which have a downwardly extending projection 19 that forms a hook-like engagement with the wall of the container 15 when the tongues 18 are pressed therethrough, as shown. The receptacle 10 16, like the receptacle 11, may also have a perforated outer wall, as at 20, which provides a grater-like finish to retain the scouring pad 12 therein.

In Figure 3 of the drawing, there is shown a 15 modified form of the pad receptacle illustrated in Figure 1 of the drawing. In this embodiment, instead of having the rearwardly and downwardly projecting tongues 13, the receptacle, designated by the numeral 21, is provided with 20 two container perforating tongues 22 at its upper corners, which may be punched through the wall of a cylindrical container. In order to hold these tongues 22 in interlocking engagement with the wall of the container 10, they each have an 25 angularly disposed detent or barb 23, which is sprung outwardly from the surface of the tongues 22. With this type of receptacle, the operator will merely press the tongues 22 through the wall of the container and thus the receptacle 30 22 will be firmly held upon the side thereof. When the soap container has been emptied, the user can remove the receptacle by pulling the tongues with their detent 23 forcibly from the container wall.

35 In Figure 4 of the drawing, there is shown a further modified form of the invention, wherein a scouring pad receptacle, designated by the numeral 24, is secured upon a cylindrical container 10 by means of a band 25. The band 25 may be of spring steel having ends which 40 substantially meet at the side of the container 10 opposite the receptacle 24, or it may be an ordinary elastic band which can be stretched around the container 10. As shown in this embodiment, the band 25 is secured to an 45 up-standing curved wall 26 of the receptacle 25 by passing it through two slots 27 at the upper corners thereof. Between these slots 27 there is formed a tongue-like portion 28 which can be 50 bent out to permit a placing of a continuous band through the slots 27, after which the tongue-like portion 28 is bent back flush with the wall 26 of the receptacle 24. In this embodiment, in order to prevent a slipping or displacement 55 of the receptacle 24 upon the wall of the container 10, as when soap is being shaken therefrom, the back wall 26 of the receptacle 24 is also provided with a grater-like surface, as at 29. When this grater-like finish 29 is provided 60 upon the container engaging surface of the receptacle 24, it will be readily seen that the band 25 will cause it to seat into the outer surface of the container 10 and thus prevent any 65 slipping of the receptacle 24 when the container 10 is in use.

In Figure 5 of the drawing, there is shown a

further modified form of container engaging means for the receptacle. In this embodiment the receptacle, designated by the numeral 30, is provided with two spike-like projections 31 having barbs 32 thereupon. The barbs 32 preferably 5 extend downwardly and thus interlock with the wall of the container when the receptacle is secured thereupon. It will be understood that this latter form of securing means is applicable to either a curved or a flat backed receptacle, so that it may be used with either a cylindrical or a square container.

While I have, for the sake of clearness and in order to disclose the invention so that the same can be readily understood, described and 15 illustrated specific devices and arrangements, I desire to have it understood that this invention is not limited to the specific means disclosed, but may be embodied in other ways that will suggest themselves to persons skilled in the art. 20 It is believed that this invention is new and it is desired to claim it so that all such changes as come within the scope of the appended claims are to be considered as part of this invention.

Having thus described my invention, what I 25 claim and desire to secure by Letters Patent is—

1. An attachable steel wool scouring pad receptacle for a cardboard container, comprising an open topped narrow receptacle having a container engaging wall, and container perforating 30 means carried by said container engaging wall for attaching the receptacle to a cardboard container, said container perforating means having a barb-like extension positioned at a point from the container engaging wall corresponding 35 to the thickness of the wall of said container.

2. An attachable steel wool scouring pad receptacle for a cardboard container, comprising an open topped narrow receptacle having a container engaging wall, container perforating projections 40 extending at a right-angle from said container engaging wall for attaching the receptacle to a cardboard container, and means upon said perforating projections for securing same without bending in the wall of the container.

3. A scouring pad holder for use with shaker type soap containers and the like, comprising a receptacle for a scouring pad having a container engaging wall, container perforating 50 means upon the container engaging wall of said receptacle for securing it upon a soap container, and means extending inwardly from an inner wall of the receptacle adapted to engage and retain a pad therein against displacement when the soap container is shaken to discharge soap 55 therefrom.

4. A steel wool scouring pad receptacle for a soap container of the character described, characterized by the fact that one of the walls 60 of said receptacle is perforated to provide a grater-like inside surface for holding a steel wool pad therein against accidental displacement upon a shaking of the soap container.

65 DORA MADSEN.
